(57) **CLAIM**

The ornamental design for attachable eyeglass earplugs, as shown and described.

DESCRIPTION

FIG. 1 is an isometric view of the attachable eyeglass earplugs according to the present application.

FIG. 2 is a front view of the attachable eyeglass earplugs.

FIG. 3 is a back view of the attachable eyeglass earplugs.

FIG. 4 is a left view of the attachable eyeglass earplugs.

FIG. 5 is a right view of the attachable eyeglass earplugs.

FIG. 6 is a top view of the attachable eyeglass earplugs; and,

FIG. 7 is a bottom view of the attachable eyeglass earplugs.

(Continued)

The broken lines shown in the drawings depict environmental subject matter and form no part of the claimed design.

1 Claim, 5 Drawing Sheets
